United States Patent Office.

EDWARD F. COFFIN, OF NEWBURYPORT, MASSACHUSETTS.

Design No. 3,986, dated April 26, 1870.

DESIGN FOR COMBS.

The Schedule referred to in these Letters Patent and making part of the same.

To all whom it may concern:

Be it known that I, EDWARD F. COFFIN, of Newburyport, in the county of Essex and State of Massachusetts, have invented and produced a new and original Design for Combs, of which the following is a specification.

The nature of my invention is fully represented in the accompanying drawing, to which reference is made, and consists in giving to the back of the comb a scroll

form in its transverse section, as shown in Figure 2, which is an end view of the comb, and Figure 1 a side view thereof.

I claim as my invention—

The design for a comb, as shown.

EDWARD F. COFFIN.
